UNITED STATES PATENT OFFICE.

DANA H. BENJAMIN, OF CLEVELAND HEIGHTS, OHIO, ASSIGNEE TO HENRIETTA C. BENJAMIN, OF CLEVELAND HEIGHTS, OHIO.

REVERSING MECHANISM FOR WASHING MACHINES.

1,403,285.

Specification of Letters Patent. Patented Jan. 10, 1922.

Application filed October 6, 1919. Serial No. 328,873.

To all whom it may concern:

Be it known that I, DANA H. BENJAMIN, a citizen of the United States, residing at Cleveland Heights, in the county of Cuyahoga and State of Ohio, have invented certain new and useful Improvements in Reversing Mechanism for Washing Machines, of which the following is a specification.

This invention relates to reversing mechanism and particularly to that type of such mechanism utilized for driving and operating the cylinder of a washing machine.

In operating cylinder washing machines it is necessary to rotate the cylinder in one direction for several revolutions and in the opposite direction for a like number of revolutions. It is desirable that the reversals of the drum should take place with as little jar as possible to prevent undue strain upon the parts and to do away with undesirable noise. Washing machine cylinders have been operated in this manner by friction gearing and various other types of mechanism but the present invention relates particularly to a type of gearing wherein two oppositely driven members or gears are coupled or connected to drums on the main driven shaft by brake bands controlled automatically from the gearing itself, all of the parts being arranged in such manner that when the driven members or gears are in motion the cylinder will receive its proper number of rotations in each direction and will be started in each direction with ease and without shock.

Further features of the invention will more fully and at large appear from the following description, drawings, and claims.

Referring to the drawings, Fig. 1 is a side elevation of a washing machine provided with my improved gearing; Fig. 2 is an end elevation from the right in Fig. 1; Fig. 3 is an enlarged vertical sectional view on the line 3—3, Fig. 2, showing parts in section and in elevation; Fig. 4 is a section taken upon the line 4—4, Fig. 3 looking to the left; Fig. 5 is a sectional view taken upon the line 5—5, Fig. 3, also looking to the left, parts being omitted for clearness of illustration; Fig. 6 is a sectional view taken substantially upon the line 6—6, Fig. 2; Fig. 7 is a detail section on the line 7—7, Fig. 3; and Fig. 8 is a detail view, corresponding to Fig. 5 and showing another position of the parts.

In the drawings, 1 represents a suitable

tub or casing supported on legs 2 and provided at one end with a bearing member 3 having a V-shaped notch 4 therein for receiving a trunnion of the cylinder, as will appear. At the opposite end of the tub or 60 casing 1 is a bearing 5 secured to the tub and provided with a recess 6 for reception of a suitable packing adapted to bear against a main tub operating shaft 7 which projects into the tub and is provided with a driving 65 head 8 having oppositely extending arms each provided with a socket 9. These sockets receive plugs 10 secured to a driving member 11 secured to the head of the washer cylinder 12. The opposite head of the cylinder is provided with the trunnion member 13 provided with a trunnion 14 adapted to engage in the socket 4. The cylindrical wall 15 of the washer is perforated as is usual in machines of this type, there being only a 75 few of the perforations shown.

It will be seen from the foregoing that the washer cylinder is supported at both ends and may be driven by means of the shaft 7.

Secured to the end wall of the tub or casing 1 by means of a flange 16 is a gear casing 17. The flange 16 provides a bearing for the shaft 7, as shown in Fig. 3, and another bearing 18 is provided for the outer end of said shaft in the cover 19 of said gear casing. 80

Secured to the shaft 7 within the casing 17 are drum hubs 20 and 21 supporting cylindrical drums 22 and 23 respectively. These drums are engaged by suitable bands which are automatically operated to drive 90 the shaft 7 in opposite directions, as will fully appear.

Rotatably mounted upon the hub 20 is a drum driving gear 24, which is provided with a shaft 25 preferably mounted in a 95 suitable bearing forming a part of one of the spokes and located near the periphery of the gear. This shaft 25 is provided with a band operating lever 26 having a pair of spaced arms 27 extending in one direction 100 from the shaft and a pair 28 extending in the opposite direction, the former being pivotally connected to a band pull rod 29 and the latter being connected to a pull rod 30. The pull rod 29 extends through a block 31 105 pivotally mounted in ears 32 secured to one end of the band 33. On the rod 29 is an adjustable nut 35 for regulating the pressure of a compression spring 34 which transmits yielding pull of the rod 29 to the band 33. 110

The pull rod 30 in like manner passes through a block 36 pivotally mounted in ears 37 formed on the opposite end of the band 33. A pressure spring 38 and adjusting nut 39 are also provided for rod 30. When the shaft 25 is rotated in the clockwise direction, as shown in Fig. 7, the band 33 will be tightened upon the flange of drum 22 and the gear 24 will be coupled to drive 10 the washer cylinder in one direction.

Secured to the shaft 25 on the opposite side of the gear 24 is an operating lever 40 provided with a stop portion 41 adapted for engagement with a pin 42 carried by the gear to limit the movement of the lever. The inner end of the lever 40 extends toward the shaft 7 and is provided with a friction roller 43 adapted for engagement with a cam flange 44 secured to the side of a cam gear 45 loosely mounted upon the shaft 7. This cam gear 45 meshes with a cam pinion 46 rotatably mounted upon a pin 47 secured in the gear 24. Rigidly secured to the pinion 46 is a planetary reduction gear 48 which meshes with a stationary gear 49 surrounding the shaft 7 but held against rotation by means of a pin 50 passing through an eye 51 forming a part of a bracket 52 which extends downward and is provided with 20 two shaft bearing portions 53 and 54 and two arms 55 and 56 secured by bolts 57 in an extension 58 of the gear casing, as shown clearly in Figs. 3 and 4. As the gear 48 rolls planetwise around the stationary gear 49 it causes gear 45 and the cam 44 to rotate around shaft 7 in the same direction as member 24 but at a slower rate. This differential movement between members 24 and 45 causes member 24 to overtake member 45 by a complete revolution in a given number of revolutions of member 24 depending upon the relative sizes of the planetary gears, as will be readily understood.

When the gear 24 is rotated the band operating mechanism is carried bodily around by it and while the roller 43 moves along the cam flange 44 the band 33 is tightened, this effect continuing during a number of revolutions of the gear 24 depending upon the 45 length of flange 44 and the relation of the planetary gears, as before stated. Since the band wheel is rigidly secured to the shaft 7 the washer cylinder will also be driven. The cam flange 44 is substantially 50 of the form shown in Fig. 5, is less than a semi-circle in extent and is provided with a downwardly extending portion 59 adapted for elevating the roller 43 onto the concentric or main portion of the flange. The opposite end of the flange is provided with a curved portion 60 which forms a quick release for the lever 40. Springs 40^a tend to release the band 33 and swing the lever 40 inwardly toward the cam flange.

65 A similar set of gears and cams is pro-

vided for the drum or band wheel 23 except that the cam 44 of this set is so located that it is diametrically opposed to the first cam, or to the one first described, the object being to cause one band operating mechanism to be in action while the other is inactive, etc. The gears 24 are identical, as before stated, but they are driven in opposite directions and the mechanism performing this function will now be described.

Referring to Fig. 6, it will be seen that the two gears 24 mesh with pinions 61 and 62 the former being mounted upon a shaft 63 supported in the bearing 54 of the bracket 52 and in a bearing 64 formed in the 70 cover 19 opposite to the extension 58 of the gear casing.

The pinion 62 is wider than the gear 24, is mounted upon a short shaft 65 supported in the bearing 53 and meshes with a pinion 66 75 keyed to the shaft 63. The shaft 63 extends beyond the bearing 64 through a clutch housing 67 formed on the cover plate 19 and into a bearing 68 provided upon a clutch housing cover 69. Within the clutch housing thus formed the shaft 63 is provided with clutch member 70 loosely splined upon the shaft 63 and adapted to be actuated by a yoke 71 engaging the peripheral groove 72 of the clutch member. This 85 clutch member is provided with a socket 73 adapted to receive the pin 74 slidably mounted in a driving gear 75, and yieldingly held in an outward position by a spring 76.

The driving gear 75 is loosely mounted upon the shaft 63, is held in place by a collar 77 and is driven by a driving pinion 78 operated from a suitable motor 79. The yoke 71 forms part of an operating lever 105 80 which extends out to a convenient point for operation. It will be seen from the foregoing mechanism that the two gears 24 are driven in opposite direction and that the power may be applied as desired by the 110 clutch.

Each gear 24 is preferably provided with a counterweight 24^a diametrically opposite to the shaft 25 and associated parts, although this is not essential.

What I claim is:—

1. In combination, an operating shaft, and driving means therefor, comprising a drum connected thereto, a brake band arranged to frictionally seize said drum, means for rotating said band to drive the drum, and automatic means governed by the rotation of the band and independently of the rotation of the drum for actuating said band to seize and release the drum.

2. In a washing machine reversing mechanism, the combination of an operating shaft, and driving means therefor, comprising a drum connected thereto, a brake band arranged to frictionally seize said drum,

means for rotating said band to drive the drum, a movable member for actuating said band to seize and release the drum, and an operating cam over which said member travels.

3. In a washing machine reversing mechanism, the combination of an operating shaft, and driving means therefor, comprising a drum connected thereto, a brake band arranged to frictionally seize said drum, means for rotating said band to drive the drum, a movable member for actuating said band to seize and release the drum, an operating cam over which said member travels, and means for rotating said cam in the same direction as said band.

4. In a washing machine reversing mechanism, the combination of an operating shaft, and driving means therefor, comprising a drum connected thereto, a brake band arranged to frictionally seize said drum, means for rotating said band to drive the drum, a movable member for actuating said band to seize and release the drum, an operating cam over which said member travels, and means for rotating said cam in the same direction as said band at a different rate of speed.

5. In a washing machine reversing mechanism, the combination of an operating shaft, and driving means therefor, comprising a drum connected thereto, a brake band arranged to frictionally seize said drum, means for rotating said band to drive the drum, a movable member for actuating said band to seize and release the drum, an operating cam over which said member travels, and planetary gearing for producing differential rotation of said band and cam.

40 6. In combination, an operating shaft, and

reversing mechanism therefor, comprising a pair of drums connected to said shaft, a brake band for each drum, means for rotating said bands in opposite directions, and means for alternately operating said bands to seize the drums.

7. In combination, an operating shaft, and reversing mechanism therefor, comprising a pair of drums connected to said shaft, a brake band for each drum, means for rotating said bands in opposite directions, and two cams, one for operating each band.

8. In combination, an operating shaft, and reversing mechanism therefor, comprising a pair of drums connected to said shaft, a brake band for each drum, means for rotating said bands in opposite directions, two cams, one for operating each band, and means for rotating each cam with its respective brake band.

9. In combination, an operating shaft, and reversing mechanism therefor, comprising a pair of drums connected to said shaft, a brake band for each drum, means for rotating said bands in opposite directions, two cams, one for operating each band, and means for rotating each cam with its respective brake band, but at a different rate of speed.

10. In combination, an operating shaft, and reversing mechanism therefor, comprising a pair of drums connected to said shaft, a brake band for each drum, means for rotating said bands in opposite directions, two cams, one for operating each band, and planetary gearing operated by rotation of said bands for also rotating said cams.

In testimony whereof I affix my signature.

DANA H. BENJAMIN.
